UNITED STATES PATENT OFFICE.

OLIVER H. GARDNER, OF NEW BEDFORD, MASSACHUSETTS, ASSIGNOR OF
ONE-HALF TO TIMOTHY J. COUGHLAN, OF SAME PLACE.

SCAFFOLD-FASTENING.

SPECIFICATION forming part of Letters Patent No. 432,996, dated July 29, 1890.

Application filed March 29, 1890. Serial No. 345,855. (No model.)

To all whom it may concern:

Be it known that I, OLIVER H. GARDNER, a citizen of the United States, residing at New Bedford, in the county of Bristol and State of Massachusetts, have invented a new and useful Improvement in Scaffold-Fastenings, of which the following is a specification.

The object of my invention is to provide a device by means of which scaffolding may be 10 clamped together without injuring or weakening it, so that it may be used again and again; and it consists in a round bar of metal having mounted thereon eccentrically a roller provided with a lever, by means of which it 15 may be partially revolved on its axis, and a chain provided at one end with a hook and secured to said bar and adapted to embrace the upright and ledger of a scaffolding to 20 secure them together and be tightened by means 25 of said eccentrically-mounted roller on said shaft.

The accompanying drawings illustrate my invention, in which Figure 1 represents a side view of my invention as it appears when in 25 use, and Fig. 2 represents a front view of the same.

Similar letters refer to similar parts throughout the several views.

a represents the upright of a section of 30 scaffolding, and *b* represents the horizontal beam, or, as it is commonly called, the "ledger."

c represents a round bar of metal, provided 35 with a head *i*, and having loosely mounted thereon the eccentric roller *d*, provided with the handle or lever *h*.

g represents a chain, one end of which is provided with a hook *e*.

The bar *c* is passed through the eccentric roller *d*, and then through a link in the chain *g* near the hook. The end of the bar *c* is then 40 upset or provided with some suitable device to prevent the chain from slipping off.

The operation of the device is as follows: The ledger being held in place on the upright, 45 the device is placed against it with the thin part of the eccentric roller bearing against the ledger and the lever *h* uppermost, as shown in Fig. 1. The chain *g* is then carried upward and around the upright *a* and forward over 50 the bar *c* and under the ledger and again around the upright, and then forward and secured to the hook *e*. The eccentric *d* is then partially revolved on its axis by means of the lever *h* until the chain is sufficiently tight to 55 hold the ledger in place, as shown in Fig. 2.

Having thus described my invention, what I claim, and desire to secure by Letters Patent, is—

A scaffold-fastening device consisting of a 60 round bar of metal having loosely mounted thereon eccentrically a metallic roller provided with a lever, by means of which it may be rotated on its axis, a chain provided at one end with a hook and secured to said bar, and 65 adapted to embrace the upright and ledger, substantially as and for the purpose shown and described.

OLIVER H. GARDNER.
